UNITED STATES PATENT OFFICE.

FRANK BILLINGS AND ROBERT P. GREENLEAF, OF CLEVELAND, OHIO; SAID GREENLEAF ASSIGNOR TO SAID BILLINGS.

LOADING MACHINE.

Application filed September 16, 1918. Serial No. 254,262.

To all whom it may concern:

Be it known that we, FRANK BILLINGS and ROBERT P. GREENLEAF, citizens of the United States, and residents, respectively, of Cleveland, in the county of Cuyahoga and State of Ohio, and Cleveland, in the county of Cuyahoga and State of Ohio, have invented a certain new and useful Improvement in Loading Machines, of which the following is

10 a full, clear, and exact description.

This invention relates to loading apparatus, and is in some respects an improvement over the construction constituting the subject matter of our prior application filed 15 July 9, 1917, Serial No. 179,301, renewed February 21, 1918, Serial No. 218,592, now Patent No. 1,286,168, issued November 26, 1918.

In our prior application we disclosed a 20 loading machine including a ram adapted to be moved forwardly and rearwardly and having guide-ways for a device in the form of a trolley or carriage designed to be reciprocated relative to the ram and carrying a 25 digging and conveying element in the form of a bucket or shovel. By the provision of suitable gearing including a rack carried by the ram, and gears concentric with the pivotal axes of arms connecting the shovel to 30 the trolley or carriage, when the latter is shifted, the arms and shovel are given a combined movement of translation and rotation so as to carry the shovel from a point in front of the machine, rearwardly and back 35 over the machine to dumping point, and from the dumping point back to digging position, the shovel being filled on the forward stroke of the ram.

The present invention has for its chief objects the provision of means whereby in a 40 machine of the general type above described, the shovel will be given a greater linear movement while being turned so as to carry it over the machine so that the shovel will 45 discharge well toward the middle of the car which is designed to receive the material at the rear of the machine. Additionally the invention aims to provide means whereby the desired linear and rotary movements are 50 obtained with relatively small gears, and with the gears and racks located well above the ground, and the racks which impart the

rotary movement inverted, so that they are not easily fouled with dirt or ore.

Still further the invention aims to provide an improvement in the form of connecting means or arms between the shovel and the trolley or carriage designed to prevent the shovel being extended upwardly more than a predetermined distance above 55 the machine, while the swinging and rotary movements are taking place, and which in fact swing or move in such fashion that the point of the shovel is never any higher at any part of the path of the swinging movement than when in the discharging position at the rear of the machine.

Further the invention aims to provide a machine having a large range of movement so that the digging and conveying member 70 can be caused to operate on the material throughout a predetermined range which depends upon the length of the ram stroke.

The invention may be briefly summarized as consisting in certain novel details of construction and combinations and arrangements of parts which will be described in the specification and set forth in the appended claims.

In the accompanying sheets of drawings, 80 Fig. 1 is a side elevation of our improved machine with the shovel shown in full lines in dumping position, and by dotted lines in various other positions between the dumping and digging positions; Fig. 2 is a top 85 plan view of the same with the shovel omitted, and the shovel supporting arms broken away; Fig. 3 is a side view with the machine extended and also swung to position at right angles to the frame, or at right 90 angles to the position shown in Figs. 1 and 2; Fig. 4 is a detail sectional view through the trolley and through the shovel swinging gears associated therewith; Fig. 5 is a partial front view of the machine showing the 95 forward end of the ram; Fig. 6 is a rear view of the machine with the shovel in dumping position; Fig. 7 is a sectional view substantially along the line 7—7 of Fig. 1; and Fig. 8 is a partial transverse sectional view substantially along the line 8—8 of Fig. 1.

The machine includes a truck 10, with wheels 11, designed to run over the rails of a track 12 to which the machine may be

clamped with quick acting screw track clamps 13, which can be hooked over the ends of the machine, and require no bolts for their attachment. The truck can be 5 braced against tipping when the digging and conveying mechanism is swung to one side of the machine by quick acting jack arms 14 which can be attached to the truck by hook plates and require no bolts, one of the 10 jack arms being shown in Fig. 3.

In addition to the parts above mentioned, the truck includes a semi-circular track 15 and a fixed gear 16 acting as a fifth wheel for supporting the superstructure.

15. Mounted on the truck by means of a pivotal kingpin 17 (see Fig. 8) at the center of the fixed gear, and by means of rollers 18 engaging the semi-circular track is the superstructure consisting of the digging, 20 swinging and dumping mechanism and supporting parts designed to be swung on the truck through a complete semi-circle so that material at the sides as well as in front of the machine can be reached and loaded into cars brought up to the rear of the machine.

This superstructure includes a large cylinder 19, forming part of the reciprocating motor which actuates the ram, this motor and two additional motors to be referred to, 30 being preferably actuated by compressed air, though it is not essential to our invention that air motors, or even reciprocating motors be employed, for we now contemplate manipulating the operating parts embodying the features of this invention by 35 one or more electric rotary motors.

This cylinder 19 which extends lengthwise of the superstructure and is fixed relative thereto, is supported at its rear end by 40 the fixed gear 16, and forwardly of the gear by the rollers 18.

At opposite sides of this cylinder are U-shaped guides or trackways 20, each consisting in this case of angles forming outwardly facing channels. These guide-ways are fixed relative to the cylinder 19. Though these U-shaped guides or track-ways 20 may be formed in other ways than herein illustrated, in Fig. 7 each guide-way is shown as 45 composed of an upper angle, and a lower angle 20^a having their horizontal flanges facing outwardly and their vertical flanges overlapping so that they may be secured together and to a part 20^b which may be a 50 part of the cylinder 19 or a member secured thereto.

The plunger 21 of the cylinder 19 actuates a forwardly and rearwardly reciprocating ram formed in two parts, each at one 60 side of the cylinder, and each part composed of two angles 22, spaced apart, forming a slotted guide or runway, each extending substantially the full length of the ram. The forward ends of the two parts of the 65 ram are connected to a heavy cross-head 23;

to which the piston rod of the cylinder 19 is connected, as shown in Fig. 1. Additionally the side sections of the ram are connected together from their rear ends to about the middle of the ram by a cylinder 70 24 of a trolley actuating motor.

This ram and the parts carried by it are mounted for reciprocating movements in the guide-ways 20 by rollers 25 carried by the rear portions of the ram, and the ram 75 is further supported by rollers 26 carried by the forward ends of the guide-ways and engaged by the ram.

Arranged to run lengthwise of the slots of the ram between the angles 22 composing 80 each side thereof, is a trolley or carriage 27, each side formed by an angle 28 having a pair of spaced rollers 29 engaging the flanges of the angles forming the guide-way or slot at the corresponding side of the ram. 85 This trolley is actuated by a cross-head 30 connected to the plunger 31 of the upper cylinder 24, which as before stated, is carried by the ram and connects together the 90 two sides thereof.

This cross-head, as will be seen by Fig. 7, has at its ends a pair of pinions 32 which engage two pairs of racks including two upper racks 33 and two lower racks 34 carried by the angle members 28 on the two 95 sides of the trolley. The upper pair of racks are connected to the upper portions of the two sides of the ram by U-shaped crosspieces 35, whose ends are attached to angles 36 secured to the upper pair of angles 100 22 of the ram. It might be mentioned at this point, that the cross-head 30 which reciprocates the pinions 32, has a pair of Z-shaped guide members 37 (see Fig. 7) whose upper outer ends slide in grooves of 105 guide-ways formed between the racks 33 and bars 38 attached to the U-shaped cross-members 35.

Thus it will be seen that as the cross-head is reciprocated relative to the ram, the 110 pinions 32 are carried backwardly or forwardly, and since they engage the relatively stationary racks 33 (carried by the ram) and the racks 34 carried by the trolley, the trolley 27 is reciprocated and is given twice 115 the movement of the cross-head, and is actuated at twice the speed of the cross-head. Through this mechanism including the rack and pinion gearing by which the movement of the cross-head 30 is multiplied, or by 120 which the stroke of the trolley is made twice as great as the stroke of the actuating plunger and cross-head 30, the desired linear movement is imparted to the shovel supporting arms, while at the same time the angular 125 or rotative movement is imparted to the shovel supporting arms as will be described shortly.

The material is picked up from in front of the machine and loaded into cars which 130

are run up onto the track at the rear of the machine, one of these cars being shown at 39 in Fig. 1, by a shovel 40, similar to that shown in our prior application, this 5 shovel having a lower digging edge and an open front so that the material can be scooped up on the forward stroke of the ram. As in our prior application, this shovel is given a combined rotary move- 10 ment and movement of translation so as to cause it to be moved from a position in front of the machine upwardly and rearwardly to dumping position and forwardly and downwardly again to digging position, but 15 the mechanism for accomplishing this is specifically different from that shown in our prior application, and has certain advantages over the latter.

In accordance with our present invention, each side of the trolley has a gear 41 which meshes with an overhead inverted rack 42 instead of a lower rack whose teeth project upwardly as in our prior application, but in view of the long movement of 20 the carriage in this instance, as evidenced by the length of the racks 42 which are carried by the ram and extend throughout the major portion of the length of the latter, not only in one stroke of the trolley would 25 a greater angular movement be imparted to these gears 41 than could be imparted to the shovel and the arms connecting it to the trolley, but since the racks 42 are inverted, the gears 41 rotate in the opposite direction to the rotation of the shovel and shovel 30 supporting arms. We therefore employ a form of compound gearing to cause the linear movement imparted to the trolley to impart rotary movement to the shovel, and 35 provide at the side of each gear 42, which is preferably mounted on the pin 43 which supports the forward roller 29 of the trolley (see Fig. 4) a pinion 44, which pinion rotates with the associated gear 41 and may 40 be integral therewith as indicated in Fig. 4, or, of course, may be a separate pinion secured to the gear 41. Each pinion 44 meshes with a gear 45 and rotates it in the opposite direction to the rotation of 45 the pinion 44, which gear 45 is journaled on the pin 46 which supports the rear roller of the trolley, this pin being fixed in position. The direction of rotation of the gears 45, (one at each side of the trolley) is the 50 same as the direction of rotation of the shovel supporting arms, and the sizes of the gears are so selected that with a given stroke of the trolley the desired angular movement is imparted to the gears 45, which 55 angular movement is the same as the angular movement of the shovel supporting arms in their travel from digging position to dumping position, and vice versa.

Fixed to these gears 45 in any suitable 60 manner so as to rotate therewith, are a

pair of shovel supporting arms 47, and pivoted to the outer end of these arms at 48 are two additional shovel supporting arms 49, which are secured to the sides of the shovel 40 by bolts or otherwise. The 70 angular positions of the arms 49 and shovel 40 can be adjusted to adapt the lower digging edge of the shovel for any selected depth of cut.

In addition to these pivoted arms 47 and 75 49, certain links are utilized to control the relative angular positions of the arms and to change the relative positions of the arms as the shovel is passing through its cycle of movement, and thereby control or limit the 80 path of movement of the highest point of the shovel in its swinging movement over the machine. These links include relatively long links 50 which are pivotally connected at 51 to the forward arms 49 a short 85 distance beyond the pivotal points 48. The lower or inner ends of these links 50 are pivotally connected at 52 to relatively short links 53 which in turn are pivoted at 54 to short fixed arms 55 which are 90 secured to the fixed roller supporting pins 46. These arms 55 at all times project rearwardly substantially as shown in Fig. 1 and in Fig. 3. Each arm 55 is provided with a shoulder 55^a which is engaged by 95 one face or edge 53^a of the associated short link 53 to limit the movement of the link in one direction relative to this arm, and the shoulder 55^a is engaged by a second shoulder 53^b of the link to limit its swing- 100 ing movement relative to the arm in the opposite direction. Likewise each of the arms 49 has a shoulder 49^a which is adapted to be engaged by one edge of the associated arm 47 to limit the swing of the 105 arm 49 in one direction relative to the associated arm 47.

The mechanism so far described, operates in the following manner. Starting with the parts in the position shown in Fig. 1, which 110 shows the shovel in its extreme rear or dumping position, the cross-head 30 connected to the plunger of the upper cylinder 24 is moved forwardly, and this movement through the racks 33 and 34 and the pinion 115 32 moves the trolley forwardly a distance equal to twice the movement of the cross-head, and sufficiently, in fact, to carry the shovel from a position well back of the machine toward the middle of the receiving car 120 39, to digging position in front of the machine. The forward movement of the trolley through the racks 42 and gears 41, 44 and 45 causes the shovel and shovel support- 125 ing arms to be swung with a combined rotary and linear movement from the dumping position shown in Fig. 1 to digging position in front of the machine, and the re- 130 verse movement of the cross-head connected to the plunger of the upper cylinder swings

the loaded shovel from the front of the machine upwardly and rearwardly to dumping position shown in Fig. 1, this taking place, of course, after the shovel has been filled by 5 a forward movement of the ram, which in Fig. 3 is shown extended and near the end of its forward filling stroke. It should be noted at this point that the combined rotary and linear movements imparted to the shovel 10 by the movement of the trolley can be given to the shovel independently of the movement of the ram, and in fact, the pistons in the cylinders of both motors may be actuated simultaneously or successively. In 15 practice the shovel will be elevated slightly after being moved outwardly to filling position, and then the pistons of both cylinders may be retracted at about the same time so that the upward and rearward swinging 20 movement of the shovel can take place while the ram is being retracted to save time, but the ram can be wholly retracted before the upward and rearward swinging movement is given to the shovel to dump the contents 25 of the shovel into the car.

When the shovel starts to swing forwardly from the position shown in Fig. 1, the links 50 for a period act as thrust or compression members to hold the shovel and arms 49 upwardly, the edges 53 of the short links then engaging the shoulder 55^a of the fixed arms 55, and as the shovel swings from its rearward position forwardly toward the overhead position, the angularity of the arms 47 30 and 49 gradually decreases at such a rate that the highest point of the shovel, which is the digging point, travels forwardly in substantially a straight line and at no part of its path of movement is it higher than the 35 shovel is in the full line position of Fig. 1.

As the shovel continues its forward movement, the arms 47 and links 50 gradually assume a crossed position, and when the center of gravity of the moving parts passes beyond 45 the vertical line, the links 50 become tension members and allow the angle between the arms 47 and 49 to gradually increase until the shoulders 49^a of the arms 49 engage the edges of the arms 47 after which all the 50 swinging parts including the arms 47 and 49 and links 53 swing as a unit said links 53 then turning about the axes 54 to permit this action and the shoulder 53^b engaging the shoulders 55^a when the shovel reaches its 55 lowermost position. If the trolley is permitted to move forwardly to the limit of its forward permissible movement, the shoulders 53^a and 55^a engage, but otherwise they do not.

60 When in digging position, shown in Fig. 3, the links 50 resist collapsing of the arms 47 and 49 under the thrust created by the forward movement of the shovel into the material, these links then acting as struts or 65 compression members, but when power is

applied through the gearing to the arms 47 to elevate the shovel, the links will not prevent this movement nor the relative shifting of the arms 47 and 49 during the backward and upward travel of the shovel to dumping 70 position.

To permit rapid operation of the machine, buffers are provided to limit the rearward and forward swinging of the parts and the rearward and forward movements of the 75 trolley, and in addition the forward buffers which are capable of adjustment, are utilized to vary the forward travel of the trolley relative to the ram, and hence the height of the shovel from the ground, this being of importance when it is desired to vary the plane 80 of cut.

The buffers which limit or stop the rearward movement, consist of pins or plungers 56 (see particularly Fig. 2), the rear ends of these plungers having laterally extended portions 56^a adapted to be engaged by the arms 47 as the latter are approaching the end of their rearward swinging and linear movement. These plungers 56 which are carried by the ram, are surrounded by buffer springs 57, each located between one of the guides 58 for the plunger and a shoulder 59 movable with the plunger.

The forward movement of the trolley is 95 checked yieldingly by an adjustable device at the forward end of the ram, this device consisting of a pair of yieldable plungers 60, surrounded by coil springs 61 and carried at the outer ends of a cross-piece 62 at 100 the extreme front end of the ram, these plungers 60 being in the path of movement of, and adapted to be engaged by the forward rollers 29 of the trolley. This cross-piece 62 at its center has threaded engagement with an adjusting screw 63 rotatably mounted between the outer end of the ram and a flange of a Z-shaped supporting member 64 carried by the forward end of the ram. By turning the screw 63, the position 110 of the buffers or yieldable plungers 60 can be adjusted, and thus the distance that the trolley moves forwardly relative to the ram can be varied independently of the cylinder which actuates it, and since the rotary movement of the shovel and shovel supporting arms is derived from the movement of the trolley, by stopping the forward movement of the trolley at varying distances from its extreme forward movement, the height of 115 the digging edge of the shovel can be varied. In addition to the buffers above described, cushioning effects can be obtained in the cylinders through the compression of air in a well known manner.

When the material is located at any considerable distance from the center of the track, it will be necessary to swing the superstructure about the axis of the kingpin, and this is accomplished in this case by 120 125 130

a third motor including a small cylinder 65 whose plunger 66 carries a rack 67 (see Fig. 2) which rotates a pinion 68 meshing with the fixed gear 16, it being understood that the pinion 68 as well as the rack and cylinder which operate it are carried by the superstructure so that all these parts can turn with reference to the axis of the gear 16 which is the center of movement of the 10 superstructure.

Thus it will be seen that with the mechanism above described, the trolley is actuated through the two pairs of racks 33 and 34, and the pinions 32, so as to have the long 15 linear movement which is imparted to the shovel supporting arms, and when combined with the rotary movement is such that material will be carried from in front of the machine and dumped or discharged well 20 back of the machine, and preferably near the middle of the car to minimize spillage, and to do away with the necessity of a laborer to level or spread the material dumped into the car.

25 Additionally it will be seen that by the compound gearing by which rotary movement is imparted to the shovel and shovel supporting arms, the right angular movement is imparted to the shovel and arms 30 without requiring exceedingly large gears, and the gears as well as the racks which co-operate therewith may be located well above the ground, and furthermore the racks which 35 co-operate with these gears may be inverted so that they are not easily clogged with dirt.

Finally it may be noted that the ram is covered entirely by a metal roof 70 which excludes dirt from the gearing and other operating parts, this being particularly useful 40 in view of the fact that the shovel loaded with material is swung over the machine. There is only one pair of racks with teeth 45 extending upward, but these racks are well under the cover or roof 70, so that dirt or other material is not liable to lodge between their teeth.

The particular advantage of the supporting mechanism for the shovel, i. e. the mechanism connecting the shovel and the trolley 50 lies in the fact that with the pivoted arms and the links which control the angularity or relative swinging movement of these arms, the path of movement of the highest point of the shovel can be controlled with the 55 parts working smoothly and without binding, regardless of the position of the shovel and of the supporting parts associated with it.

Having described our invention, we claim: 60

1. In a loading machine, a frame or truck, a shovel adapted to be filled with material at the front of the machine, means for giving 65 said shovel a filling stroke, and additional means for giving said shovel a combined rotary movement and a movement of transla-

tion over the machine, said means comprising a forwardly and rearwardly reciprocating power actuated device, a second forwardly and rearwardly reciprocating device connected to the shovel, and mechanism between 70 said reciprocating devices by which the first imparts to the second a multiplied movement.

2. In a loading machine, a frame or truck, a shovel adapted to receive material, means 75 for giving said shovel a reciprocating movement at the front of the machine and a combined rotary movement and a movement of translation over the machine, said means comprising a reciprocating ram for moving 80 the shovel forwardly and rearwardly, a carriage movable lengthwise of the ram and connected to the shovel, and mechanism for actuating the carriage including a reciprocating multiplying member, and movement 85 actuating mechanism between said actuating member and the carriage.

3. In a loading machine, a frame or truck, a shovel adapted to be filled with material 90 at the front of the machine, means for giving said shovel a filling stroke and additional means for giving said shovel a combined rotary movement and a movement of translation over the machine, said means comprising a forwardly and rearwardly movable 95 trolley, a forwardly and rearwardly movable actuating device for the trolley and multiplying gearing between said device and the trolley.

4. In a loading machine, a frame or truck, 100 a shovel adapted to be moved forwardly and rearwardly at the front of the machine, and means for giving said shovel a filling stroke and a combined rotary movement and a movement of translation over the machine 105 whereby material may be dumped at the rear thereof, said means comprising a reciprocating ram having guide-ways, a trolley movable along the guide-ways and connected to the shovel, power actuated mechanism carried by the ram for shifting the trolley, and movement multiplying gearing between said 110 mechanism and the trolley.

5. In a loading machine, a frame or truck, 115 a shovel adapted to be moved forwardly and rearwardly at the front of the machine, and means for giving said shovel a combined rotary movement and a movement of translation over the machine whereby material may be dumped at the rear thereof, said mechanism comprising a carriage or trolley connected to the shovel, and gearing for imparting rotary movement as the carriage or trolley is reciprocated comprising an inverted rack, and a gear engaging the same.

6. In a loading machine, a frame or truck, 125 a shovel adapted to be filled with material at the front of the machine, and means for giving said shovel a combined rotary movement and a movement of translation over the ma- 130

- chine, said means comprising a forwardly and rearwardly reciprocating trolley connected to the shovel, and means for imparting rotary movement during the reciprocation of the carriage or trolley comprising a rack and a train of gears, one engaging the rack and a second which derives its motion from the first and has its own rotary motion transmitted to the shovel.
- 10 7. In a loading machine, a frame or truck, a shovel adapted to be filled with material at the front of the machine, and means for giving said shovel a combined rotary movement and a movement of translation over the machine, said means comprising a forwardly and rearwardly movable trolley, arms connecting the shovel to the trolley and rotatably supported thereby, an inverted rack, and a train of gears including one engaging the rack and one connected to one of said arms.
- 15 8. In a loading machine, a frame or truck, a shovel adapted to be filled with material at the front of the machine, and means for giving said shovel a rotary movement and a movement of translation over the machine, said means comprising a forwardly and rearwardly reciprocating device, arms connecting the shovel to said device and rotatably connected therewith, a pair of racks, and two trains of gears each having a gear engaging one of the racks and a gear connected to one of the arms, said second-named gear deriving its motion from the first-named gear, but rotating slower than the latter.
- 20 9. In a loading machine, a frame or truck, a shovel adapted to move forwardly and rearwardly at the front of the machine, means for giving said shovel a forward and rearward movement at the front of the machine and a combined rotary movement and linear movement over the machine whereby material may be dumped at the rear thereof, said means comprising a forwardly and rearwardly reciprocating ram, a carriage adapted to be reciprocated lengthwise of the ram and carried by the latter, arms connecting the shovel to said carriage and rotatably connected therewith, racks carried by the ram, and trains of gears between said racks and said arms, each train of gears including a gear engaging one of the racks, and a second gear which derives its motion from the first, but is rotated at a less speed than the first, said second gear being connected to one of the arms.
- 25 10. In a loading machine, a frame or truck, a shovel, means for moving the shovel forwardly and rearwardly at the front of the machine whereby it may be filled with material and for giving said shovel a combined rotary movement and a movement of translation over the machine, said means comprising a reciprocating ram, a power actuated device movable forwardly and rearwardly
- 30 along the ram, a trolley movable forwardly and rearwardly along the ram, movement multiplying actuating mechanism between said device and the trolley, arms connecting the shovel to said trolley and rotatably connected therewith, racks carried by the ram, and two trains of gears each comprising a gear engaging one of said racks and a gear driven by the first-named gear and having a connection with one of said arms.
- 35 11. In a loading machine, a frame or truck, a shovel adapted to be filled with material at the front of the machine, means for causing said shovel to be swung over the machine so that the material may be dumped at the rear thereof, said means comprising a member movably supported by the frame or truck, a pair of arms connecting said member to the shovel, one arm connected to the shovel and the other connected to said member, and the inner portion of the first arm and the outer portion of the second arm pivotally connected together, and means for causing said arms to be moved relatively about their pivotal axes while the swinging movement of the shovel is taking place whereby the height of the shovel above the ground is controlled.
- 40 12. In a loading machine, a frame or truck, a shovel adapted to be filled with material at the front of the machine, means for swinging said shovel from in front of the machine to the rear thereof and back to the front, said means comprising a member movably supported on the frame or truck, and two pairs of arms connecting said member to the shovel, the arms of each pair being connected, one to the shovel and the other to said member, and the inner portion of the first and the outer portion of the second being connected together between the shovel and said member, and means for causing a relative angular movement between the arms of each pair during the swinging movement whereby the height of the shovel above the ground is controlled and limited.
- 45 13. In a loading machine, a frame or truck, a shovel adapted to be filled with material at the front of the machine, means for giving said shovel a combined movement of translation and a swinging movement over the machine to dumping position at the rear thereof, said means comprising a forwardly and rearwardly traveling member, arms connecting said member to the shovel and adapted to be turned during the forward and rearward movement, said arms being pivotally connected together between the shovel and said member, and one being rotatably connected to said member and the other connected to the shovel, and means for causing the angle between said arms to change while the turning movement is taking place.
- 50 14. In a loading machine, a truck or frame, a ram supported for forward and rearward

movement, a trolley adapted to be reciprocated forwardly and rearwardly along the ram, a shovel adapted to be filled with material at the front of the machine on the 5 forward stroke of the ram and be given a combined movement of translation and a turning movement over the machine, arms connecting the shovel to the trolley, means for turning said arms as the trolley is 10 shifted, said arms comprising parts one connected to the trolley, and the other to the shovel, and at a point between the trolley and shovel being pivotally connected together, and means comprising links connected to certain of said parts for causing 15 the angle between the latter to vary as the shovel is swung over the machine.

15. In a loading machine, a frame or truck, a shovel adapted to be filled with material 20 at the front of the machine, a member movably supported by the frame or truck, means connecting the shovel to said member and adapted to be turned to impart a swinging movement, said means comprising arms, one 25 extending outwardly from said member, and having its outer portion connected to the inner portion of the second arm, and the latter having its outer portion connected to the shovel and means for resisting relative turning 30 movement between said arms while the shovel is being filled.

16. In a loading machine, a frame or truck, a shovel adapted to be filled with material at the front of the machine, means for 35 causing said shovel to be given a combined movement of translation and a swinging movement over the machine, said means comprising a forwardly and rearwardly moving member, and means connecting said 40 member to the shovel adapted to be turned to impart the swinging movement, said means comprising a pair of arms, one rotatively connected to said member, and the

other connected to the shovel, and the two arms connected together between said member and the shovel. 45

17. In a loading machine, a frame or truck, a shovel adapted to be filled with material at the front of the machine, means for causing said shovel to be given a combined movement of translation and a swinging movement over the machine, said means comprising a forwardly and rearwardly moving member, means connecting said member to the shovel adapted to be turned to impart 50 the swinging movement, said means comprising arms, one connected to the shovel, and having its inner portion connected to the outer portion of the second arm, and the latter having its inner end rotatively connected to said member and means for causing 55 said arms to be moved relatively during the swinging movement of the shovel and to be held rigid against movement while the shovel is being filled with material. 60

18. In a loading machine, a frame or truck, a shovel adapted to be filled with material at the front of the machine, means for giving said shovel a combined movement of translation and a swinging movement over the 70 machine, said means comprising a trolley adapted to be moved forwardly and rearwardly, a shovel, arms connecting the shovel to the trolley, said arms being pivotally connected together and adapted to be swung 75 relatively about their pivotal axes during portions of the swinging movement of the shovel, and means comprising engaging shoulders by which the arms are held against relative swinging movement during certain 80 portions of the movement of the shovel.

In testimony whereof, we hereunto affix our signatures.

FRANK BILLINGS.
ROBERT P. GREENLEAF.
